WINDOW CONTROLLER

Application filed February 21, 1929. Serial No. 341,605.

The invention relates to window controllers for vertically sliding panes or sashes such as those of automobile bodies. The object is to provide a simple, effective and convenient mechanism, and more especially to provide a controller by which the window will be raised automatically by a spring and can be locked or firmly held at any point. The object is, also, to provide the controller with clutch means which is capable of either locking the controller mechanism or of holding it non-positively in any position, the latter for the purpose of keeping the window in position momentarily before the clutch is locked, and which can be released to permit the window to rise under the action of the spring. When the clutch is in the non-positive holding condition, the window can be lowered and will be sufficiently held against the action of the spring and of the vibration of the car while the operator shifts his hand from the pane to the locking and unlocking handle of the clutch. This handle is movable between a position in which the clutch is locked or firmly held to a position in which the clutch is free, and between these positions there is an intermediate position in which the clutch is not locked but is applied by yielding spring pressure. The clutch includes an element adapted to engage non-positively with an extended series of recesses in a segment, plate or slide connected with the controller, so as to insure that the window will be supported with sufficient security for temporary purposes before the clutch is fully applied or locked. When the clutch is locked, this element becomes a positive locking element.

In the accompanying drawings, forming part hereof:

Fig. 1 is an elevation of a door or panel of an automobile body with its window raised, the view being taken looking at the outside, with a portion of the outer wall broken away to show the controller;

Fig. 2 is an elevation looking at the opposite side of the controller, the window, a portion of which is seen, being lowered;

Fig. 3 is a section taken on the line 3—3 of Fig. 2;

Fig. 4 is a section taken on the line 4—4 of Fig. 2;

Fig. 5 is a section taken on the line 5—5 of Fig. 3; and

Fig. 6 is a section taken on the line 6—6 of Fig. 3.

The door 2 or other portion of the body has a vertically sliding pane 3. The controller 4 is located within the thickness of the pane or body enclosure, which has inner and outer walls 5 and 6, the controller being secured to the inner side of the wall 5. As illustrated in Fig. 4, the controller includes a fixed plate 7 which is supported from this wall by studs 8 and screws 9.

Secured to the inner side of this plate is a spring case 10 containing a coiled window-raising spring 11, one end of the spring being connected to a ratchet wheel 12, which is held by a dog 13.

The other end of the spring 11 is attached to a shaft 14, which passes through an opening in the plate 7 and has a controller arm 15 fixed to its outer end. The extremity of this arm carries a grooved roller 16, which acts against the bottom of the pane 3, being preferably engaged in a slotted member 17.

Also fixed to the shaft 14, or to the controller arm 15, is a slotted segment 18. This part, or its equivalent, may be operatively connected with the controller arm either directly or indirectly, but a segment which turns about the same axis as the controller arm is preferred for its simplicity.

A clutch head 19 is arranged to bear against the outer face of this segment, a friction washer or facing 20 being preferably interposed between the head and the segment. The said head has a stem 21 of square or other suitable form to keep it from turning in a hole in the plate 7, the stem passing through this hole and through the slot 22 of the segment.

At the inner side of the plate 7, the stem 20 is fixed to a hollow part 23 having a flange 24 which is slidably guided in a tube 25, the latter being fixed to the said plate and projecting through an opening in the wall 5.

A helical spring 26 is confined between the flange 24 and the plate 7 and acts to press

the head 19 against the segment 18 and the latter in turn against the plate 7.

An extended series of curved depressions 27 is formed in the face of the segment, and the face of the clutch head 19 has a recess 5 which holds a ball 28 adapted to ride in and out of said depressions.

An operating lever or finger 29 is pivoted at 30 in the inner end of the tube 25, outside the wall 5, this lever being pivoted at 10 31 to a pitman 32. This pitman extends within the hollow part 23, where it carries a cross-piece 33, which works in slotted or enlarged openings 34 in opposite sides of the 15 said hollow part.

The outer end of the tube 25 is covered by a dome 35 screwed onto the tube, the dome having a slot 36 through which the lever 29 projects.

The relation between the centers of the 20 pivots 30 and 31 is such that when the lever 29 is moved to one end of the slot 36, where it finds an abutment, the center of the pivot 31 is carried slightly past the line through the center of the pivot 30 and the center of bearing of the cross-piece (or pivot) 33 against the inner ends of the slots 25 in the 25 part 23. Consequently the clutch head 19 is locked or clamped against the segment 18, which is sustained against the plate 7. This 30 is the condition illustrated in Fig. 3, and in this condition the window can move neither up nor down. The ball 28, or its equivalent, engaging one of the depressions 27 contributes materially to the security of the locking. 35

If the lever 29 is tripped from this self-locking position, the clutch will be held by the action of the spring 26, aided by the ball 40 28. This holding will be sufficient to keep the spring 11 from raising the window, but will permit the occupant to lower the window by pulling down on a lip 37 on the upper part of the pane, the ball 28 then 45 riding into and out of the depressions 27. This position of the lever may be termed a neutral position. When the window has been lowered to the desired point, the occupant takes his hand off the pane and manipulates the lever 29 to lock the clutch. The 50 plan of the device is such that one-hand operation suffices, the window being held temporarily by the non-positive holding means until the lock is applied.

55 When the lever is turned up toward its uppermost position, it advances the pitman until the lost-motion in the slots 25 is taken up, after which the clutch is shifted sufficiently to free the segment 18 altogether.

60 Thereupon, the spring 11 operates to raise the window automatically. The upward movement of the pane can be stopped at any point and the lock applied by simply pressing down on the lever.

65 While a preferred and simple embodiment

of the invention has been described in detail, it will be understood that numerous changes may be made without departing from the essential novelty pointed out in the claims.

What is claimed as new is:

1. A window-controller of the kind described comprising a window-raising spring, mechanism including a controller arm acted on by said spring, and a device cooperative 70 with said mechanism comprising both a lock and a non-positive holding means, each operative at any position of the window to keep the window from rising, said device being operable to bring about release of the lock alone or of both the lock and the non-positive holding means, and re-application of the lock, at will.

2. A window-controller of the kind described comprising a window-raising spring, mechanism including a controller arm acted on by said spring, and a device cooperative 85 with said mechanism comprising both a lock and a non-positive holding means, each operative at any position of the window to keep the window from rising, and a single operating member by which the device is operable to bring about release of the lock alone or of both the lock and the non-positive holding 90 means, and re-application of the lock, at will.

3. A window-controller of the kind described comprising a window-raising spring, mechanism including a controller arm acted on by said spring, a lock and a non-positive holding means, each cooperative 95 with said mechanism at any position of the window to keep the window from rising, and means for releasing said lock only so that said mechanism will be restrained by said non-positive holding means at any position to which the window may be lowered, whereupon the lock can be reapplied, and for freeing the mechanism to permit the spring to raise the window automatically.

4. A window-controller of the kind described comprising a window-raising spring, a controller arm through which said spring acts, a segment connected with said arm, a clutch cooperative with said segment, resilient means for applying pressure to said clutch, and means including a manipulating device operable at will to hold said clutch against yielding, to release the clutch partially so that the window can be lowered to any position, whereupon the clutch automatically and non-positively holds the segment against the action of the window-raising spring, and to release the clutch fully so that said spring will automatically raise the window.

5. A window-controller of the kind described comprising a window-raising spring, a controller arm through which said spring acts, a segment connected with said arm and provided with an extended series of recesses,

- a clutch cooperative with said segment, said clutch including an element adapted for non-positive holding engagement with said recesses, resilient means for applying pressure to said clutch, and means including a manipulating device operable at will to hold said clutch against yielding, to release the clutch partially so that the window can be lowered to any position, whereupon it is held automatically and non-positively by said resilient means and said element against the action of the window-raising spring, and to release the clutch fully so that said spring will automatically raise the window.
6. A window-controller of the kind described comprising a window-raising spring, a controller arm through which said spring acts, a segment connected with said arm and provided with an extended series of recesses, a clutch cooperative with said segment, said clutch including a ball adapted for non-positive holding engagement with said recesses, resilient means for applying pressure to said clutch, and means including a manipulating device operable at will to hold said clutch against yielding, to release the clutch partially so that the window can be lowered to any position, to be held temporarily by said resilient means and said ball, and to release the clutch fully so that said spring will automatically raise the window.
7. A window-controller of the kind described comprising a window-raising spring, a controller arm through which said spring acts, a segment connected with said arm and provided with an extended series of recesses, a clutch cooperative with said segment, said clutch device including an element adapted for either positive or non-positive engagement with said recesses depending upon the condition of the clutch device, resilient means for applying pressure to said clutch, and means including a manipulating device operable at will to hold said clutch against yielding, to release the clutch partially so that the window can be lowered to any position, to be held temporarily by said resilient means and said element, and to release the clutch fully so that said spring will automatically raise the window.
8. A window-controller of the kind described, comprising a window-raising spring, a controller arm through which said spring acts, a segment connected with said arm, a clutch cooperative with said segment, resilient means for applying pressure to said clutch, and a self-locking operating device movable between a position in which it locks the clutch and a position in which it moves the clutch to a free condition against the action of said resilient means, said operating device having a lost-motion connection with the clutch whereby in an intermediate position of the device the clutch is yieldingly applied by the action of said resilient means.
9. A window-controller of the kind described, comprising a window-raising spring, a controller arm through which said spring acts, a segment connected with said arm, a clutch cooperative with said segment, resilient means for applying pressure to said clutch, a pivoted operating lever in operative relation to said clutch, the relations being such that said lever and clutch are locked when the lever is moved to a position which carries the point of application of the leverage past center in one direction, there being a lost-motion connection between said lever and clutch whereby the lever can be moved in the opposite direction to or through a neutral position, in which the clutch is yieldingly applied by said resilient means, to a position in which the lever moves the clutch to a free condition.
10. A window-controller of the kind described, comprising a window-raising spring, a controller arm through which said spring acts, a segment connected with said arm and provided with an extended series of recesses, a clutch cooperative with said segment, said clutch including an element adapted for non-positive holding engagement with said recesses, resilient means for applying pressure to said clutch, and a self-locking operating device movable between a position in which it locks the clutch and a position in which it moves the clutch to a free condition against the action of said resilient means, said operating device having a lost-motion connection with the clutch whereby in an intermediate position of the device the clutch is yieldingly applied by the action of said resilient means.
11. A window-controller of the kind described, comprising a window-raising spring, a controller arm through which said spring acts, a segment connected with said arm, a fixed plate contiguous said segment, a clutch having a head to bear against the face of said segment and a part at the opposite side of the plate connected with said head, a spring acting on said part to press the head against the segment, and a self-locking operating lever in operative relation to said part.
12. A window-controller of the kind described, comprising a window-raising spring, a controller arm through which said spring acts, a segment connected with said arm, a fixed plate contiguous said segment, a clutch having a head to bear against the face of said segment and a part at the opposite side of the plate connected with said head, a spring acting on said part to press the head against the segment, a self-locking operating lever, and means of lost-motion connection between said lever and said part whereby the lever is operable either to lock the clutch or to move it to free position, with an intermediate condition in which the clutch is yieldingly applied to the segment by said resilient means.
13. In a window-controller, a controller

arm, a spring connected therewith, a slotted segment connected with the arm and provided with an extended series of recesses, a fixed plate contiguous said segment, a clutch 5 having a head to bear against the face of the clutch and a part at the opposite side of said plate connected with said head through the slot in the segment, a spring acting on said part, a ball in said head to coact with said 10 recesses, and an operating lever in operative relation to said part.
